Attorney

UNITED STATES PATENT OFFICE.

WILLIAM E. BRYANT, OF DENVER, COLORADO.

ADJUSTABLE JOINTER.

Application filed September 5, 1923, Serial No. 661,095.

To all whom it may concern:

Be it known that I, WILLIAM E. BRYANT, a citizen of the United States, residing at Denver, in the county of Denver and State 5 of Colorado, have invented certain new and useful Improvements in an Adjustable Jointer, of which the following is a specification.

The present invention relates to jointers, 10 that is to tool employed by bricklayers for removing the surplus mortar between adjacent bricks, smoothing the surface of the mortar, and giving the same a particular shape in order to form a neat and finished 15 joint.

The principal object of the invention is to provide a handle which may be readily attached to different jointers, the blade or body portions of which are provided with 20 different formations.

Another important object of the invention is to improve upon devices of this nature by providing a jointer having a simple and efficient construction, one which is reliable 25 in use, inexpensive to manufacture, durable and well adapted to the purpose for which it is designed.

With the above and numerous other objects in view, as will appear as the description progresses, the invention resides in certain novel features of construction, and in the combination and arrangement of parts 30 as will be hereinafter more fully described and claimed.

35 In the drawing:

Figure 1 is an elevation of the jointer embodying my invention,

Figure 2 is a detail section taken substantially on the line 2—2 of Figure 1,

40 Figure 3 is an end elevation thereof,

Figure 4 is a detail section taken substantially on the line 4—4 of Figure 2,

Figure 5 is a detail transverse section through one of the lugs on the handle, and

45 Figures 6, 7 and 8 are detail perspective views of portions showing different modifications of the blade or body portion of the jointer.

Referring to the drawing in detail it will 50 be seen that the device consists generally of a jointer A and a handle B. The jointer A includes a blade 1 having formed on its ends the extensions 2 which overlie the blade and converge toward each other and

terminate in right angularly extending slot- 55 led lips or ears 3. The blade 1 as shown in Figures 1 to 4 inclusive is circular in cross section whereas the blades may be of any desired formation such as the blade 1^a in Figure 6 which is triangular in cross section, the blade 1^b in Figure 7 which is rectangular in cross section, and the blade 1^c in Figure 8 which is substantially rectangular in cross section and is provided with a groove 4 on one face extending longitudinally thereof.

The handle B includes an elongated shank 5 which is curved longitudinally and terminates at one end in a threaded portion 6. Headed lugs 7 project from the ends of the shank 5 and their body portions are of oblong structure such as is indicated in Figure 5. These lugs 7 are adapted to be inserted in the notches of the ears 3. A nut 8 is associated with the threaded portion 6 of the shank 5 and may be unscrewed therefrom so as to engage the adjacent ears 3 thereby drawing the heads of the lugs 7 in firm frictional engagement with the outer faces of the ears 3 and thus preventing any 75 accidental disengagement of the handle B from the jointer. It will be seen that the handle is readily disengaged from the jointer when desired by screwing the nut 80 on the threaded portion 6. 85

A tool such as I have described with its plurality of different formed blades may be packed in the bricklayer's or mason's kit and readily assembled for use. I have, in the present instance, shown and described 90 the preferred embodiments of the invention, but it is to be understood that numerous changes in the details of construction and in the combination and arrangement of parts may be resorted to without departing 95 from the spirit of the invention as herein-after claimed.

Having thus described my invention what I claim as new is:

1. In combination, a jointer including a 100 pair of notched ears, a handle including headed lugs at its ends for engagement with the notched ears, and means for forcing and holding the heads of the lugs in firm frictional engagement with the ears.

2. In combination, a jointer provided with a pair of ears, said ears provided with notches, a handle, one end of said handle

being provided with threads, lugs projecting from the ends of the handle and provided with heads, said lugs adapted to be disposed in the notches of said ears, and a nut disposed on the threaded portion of the handle adapted to be unscrewed for engaging one ear thus forcing the heads of the lugs into firm frictional engagement with

the ears all in the manner and for the purpose specified.

In testimony whereof I affix my signature in presence of two witnesses.

WILLIAM E. BRYANT.
